IGNITION COIL

Wolfgang E. Schwarzmann, Longmeadow, Mass.,
assignor to American Bosch Corporation,
Springfield, Mass., a corporation of New York

Application February 1, 1941, Serial No. 377,001

9 Claims. (Cl. 171—209)

The present invention relates to low tension and high tension ignition coils for magnetos, battery ignition systems and other ignition generators, and particularly to such coils of stationary types having magnetic cores.

More specifically, as disclosed in the preferred embodiments hereinafter described, the invention relates to an ignition coil or generating winding having one or more terminals to which an outside wire, such as that leading to the mechanical interrupter of the generator, is electrically connected by means of an insulated or live terminal connector comprising a metal strip which is electrically connected to both a terminal post for the outside wire and a conducting member for the terminals of the winding and which is mechanically fastened to but electrically insulated from the magnetic core of the winding.

The primary object of the invention is to provide a construction in which the electrical connections to the metal strip are relieved of mechanical strains imposed on them, as by repeated connection and disconnection of the outside wire to the terminal post, and also in which the connections are precluded as a practical matter from strains and crystallization resulting from continuous or severe vibration communicated to them in service particularly on airplanes. Thus the original effectiveness of such connections, even though formed by soldered joints, is preserved in normal service over extended periods, and the disastrous result that may occur in flight from an accidental loss of ignition from this cause is practically obviated.

Another object is to simplify the construction and arrangement by fastening the insulated or live terminal connector of the winding to its magnetic core by the same means as fastens the core in place across the pole shoe projections in magnetic contact therewith.

Another object is to provide an ignition coil having means in or associated with the aforesaid terminal connector for improving the result of its impregnation by preventing the loss of impregnating material from the coil at the place or places of bringing out terminals from it.

Still another object is to provide, as elements for replacement or otherwise in ignition generators, unitary ignition coils with the terminal connectors and other features herein disclosed.

Further features and advantages of the invention will be understood from the following disclosures taken in connection with the accompanying drawing showing, as examples, high tension ignition coils of stationary and impregnated types for magnetos. In the drawing:

Fig. 1 is a vertical cross section, partly in elevation, of a magneto showing an ignition coil in position therein; Fig. 2 is an end elevation of the coil, partly in section, showing one embodi-

ment of the terminal connector thereof; Fig. 3 is a plan view of one end of the coil of Fig. 2; and Figs. 4 and 5 are views like Figs. 2 and 3, respectively, of a coil with a modified form of terminal connector.

Referring now to Fig. 1, the reference numeral 1 generally represents a magneto having a frame with a lower part 2 and a removable upper part 3, the laminated magnetic rotor 4 being rotatable in periodic registry with laminated pole pieces 5 fastened in the frame 2 in contact with the permanent magnets 6. The two upper pole pieces 5 have upstanding integral arms or projections 7 providing supports for the stationary high tension ignition coil generally indicated by 8 and having primary and secondary generating windings. This coil has fastened in it a laminated magnetic core 9 the projecting ends of which are mechanically held across the arms 7 in magnetic contact therewith by screws 10, 11 extending loosely through the core into screw-threaded engagement with the arms.

In the embodiment of the terminal connector of Figs. 2 and 3, the ignition coil has an outer secondary winding with its outer terminal electrically connected to the high tension terminal 12 and its inner terminal electrically connected to the outer terminal of the primary winding, as is well known in the art. The grounded inner terminal of the primary winding is drawn through a hole 13 in the core 9, and the live outer terminal thereof and the inner terminal of the secondary winding are drawn through the two holes 14 in the insulating end disc 15 at the other end of the coil. After vacuum treatment and impregnation of the coil, as hereinafter described, the hole 13 is closed and the terminal electrically connected to the core 9 by soldering it therein, whereas the holes 14 are covered sufficiently tightly by a tinned-over brass plate or conducting member 16 and the terminals electrically connected to the member and to each other by soldering them to its outer face after pulling them through holes registering respectively with the holes 14. This member 16 has a projecting arm 17 which, out of the plane of the member, is bent around and soldered to a metal strip 18 formed of thin, hard or half-hard, and flat tinned-over brass, riveted to the terminal post 19 in electrical connection with both the member and the post. The strip has an enlarged intermediate part 20 with a hole at 21 in line with the slot at 22 at that end of core 9. The post 19 has a hole at 23 for receiving the terminal of wire 24, which leads to the live terminal of the magneto interrupter or otherwise as desired, and also has a saw slot at 25 and screw 26 to tightly clamp the wire terminal in the hole and bring about through the strip 18 the electrical

connection of the post to the conducting member 16 and the coil terminals soldered thereto.

The screw 10 passes directly through a slot at one end of core 9 to mechanically and electrically fasten the core at that end to one of the upstanding arms 1. The screw 11 passes through the slot 22 at the other end of the core, but is insulated from strip 18 by the insulating washer 21 and insulating bushing 28. Thus the inner terminal of the primary winding soldered in the hole 13 of the core 9 is grounded on the magneto frame, while the other or live primary terminal, together with the inner terminal of the high tension winding, are electrically connected to the conducting member 16 and thence through the strip 18 to terminal post 19, but are insulated from the core 9. However, the screw 11 fastens the strip 18 mechanically to the core so that the strip supports the terminal post 19, with the wire 24 fastened thereto, from the core with little or no mechanical strain on the conducting member 16 or the soldered connections of the coil terminals thereto.

It will be observed from the foregoing that the insulated terminal connector (comprising the conducting member 16 stuck or otherwise arranged on the outside face of the end disc 15, the metal strip 18 and the terminal post 19) has no part extending to the inside face of the end disc 15 where it might bring about a short circuit or electrical break-down of the coil. Also, it will be understood that the flexibility of the metal strip 18, which may result from the form or character of its connection with the conducting member 16 through the projecting arm 17 thereof, or inherently from its structure including its dimensions and form, permits the strip to be drawn down rigidly into mechanical connection with the core 9 without imposing any substantial mechanical strain on the soldered joints between the member 16 and the terminals of the primary and secondary windings of the coil. Furthermore, the pull at the post 19, particularly upon connecting and disconnecting the wire 24 thereto, is prevented to a substantial degree from being transmitted to those soldered joints as a result of the support of the post afforded by the core 9, and likewise for the strains and crystallization effects from substantially all vibration set up in the magneto in service. In this way the original effectiveness of these soldered joints is maintained over an extended period of service, and the continuity of ignition thereby made more reliable.

In the embodiment of Figs. 4 and 5, the construction is the same except that the metal strip 30 is mechanically fastened at its outer end 31, instead of at an intermediate place, to the core 9. However, the terminal post 32 is supported substantially solely by the core, and as before substantially no mechanical strain or vibration is transmitted by the strip to the soldered connections between the metal member 33 and the terminals of the primary and secondary windings.

In both embodiments, the coil 8 is subjected to vacuum treatment and impregnation. For this purpose the primary and secondary windings, with their terminals extending loosely through respective holes 13 and 14, and with the core 9 in place, are subjected to exhausting apparatus to withdraw from the coil substantially all moisture, air, etc. and, while in this condition, oil or other impregnating insulating material is forced into the coil to fill substantially all its interstices in accordance with well known prac-

tice. Upon removal of the impregnated coil, the hole 13 is sealed by soldering the grounded terminal therein, and the conducting member 16 is stuck or otherwise arranged on the end disc 15 with the terminals extending through the holes in the conducting member registering with the holes 14. The holes in the conducting member are then sealed by flowing solder over it as indicated to fill the holes and to electrically connect the live terminal of the primary winding and the inner terminal of the secondary winding of the coil to the conducting member 16 and to each other. In this way, no leakage of impregnating material from the coil can occur through the holes in the conducting member 16 or through the hole 13 in core 9, notwithstanding repeated heating and cooling periods of the magneto in service.

It will be understood that the coil with its windings, whether or not impregnated, its magnetic core, end discs and its insulated terminal connector having means for mechanical connection to the core, form a unitary element. Such an element may be installed as an original part of the ignition generator or may be provided as a spare element for replacement therein.

While but two embodiments of the invention are disclosed, it will be understood that many changes therein and variations thereof may be made and many other applications may be devised. For instance the invention may also be applied to coils with cores for use in battery ignition systems and other ignition generators, whether such coils have inside or outside secondary windings in which one or both terminals are insulated and whether they have primary windings in which one or both terminals are insulated. Such and other changes, variations and other applications are intended to be included within the broad scope of the appended claims.

Having thus described the invention, what is claimed is:

1. In an ignition generator having pole piece projections; a stationary generating winding; a magnetic core for said winding; an insulated terminal connector for said winding comprising a conducting member having an electric connection with a terminal of said winding, a terminal post having fastening means for fastening an outside wire in electrical connection therewith, and a metal strip mechanically fastened to said member and post in electrical connection with both of them; and fastening means which mechanically fastens said strip to said core and electrically insulates them and which also fastens said core across said pole piece projections in magnetic contact therewith.

2. In a high tension ignition generator having pole piece projections; a stationary coil having primary and secondary windings; an insulating end disc for said coil having holes through which extend terminals of said primary and secondary windings; a magnetic core for said coil; an insulated terminal connector for said coil comprising a conducting member on the outside of said disc and having holes which register with the holes in said disc and through which said terminals extend, means for electrically connecting said terminals to said member and to each other, a terminal post having fastening means for fastening an outside wire in electrical connection therewith, and a metal strip mechanically fastened to said member and post in electrical connection with both of them; and

fastening means which mechanically fastens said strip to said core and electrically insulates them and which also fastens said core across said pole piece projections in magnetic contact therewith.

3. In an ignition generator having pole piece projections; a stationary impregnated generating winding; an insulating end disc for said winding having a hole through which a live terminal of said winding extends; a magnetic core for said winding having a hole into which extends a grounded terminal of said winding; an insulated terminal connector for said winding comprising a conducting member arranged on the outside face of said disc with a registering hole through which said live terminal extends, a terminal post having fastening means for fastening an outside wire in electrical connection therewith, and a metal strip mechanically fastened to said member and post in electrical connection with both of them, said hole in said core and said hole in said member being sealed so as to prevent leakage of impregnating material from said winding therethrough and to electrically connect said grounded and live terminals to said core and member respectively; and fastening means which mechanically fastens said strip to said core and electrically insulates them and which also fastens said core across said pole piece projections in magnetic contact therewith.

4. In an ignition generator having pole piece projections; a stationary generating winding; a magnetic core for said winding; an insulated terminal connector for said winding comprising a conducting member having an electric connection with a terminal of said winding, a terminal post having fastening means for fastening an outside wire in electrical connection therewith, and a metal strip mechanically fastened at one end to said member and at its other end to said post in electrical connection with both of them; and fastening means which mechanically fastens said strip to said core intermediate of said member and post and electrically insulates said strip and core and which also fastens said core across said pole piece projections in magnetic contact therewith.

5. In an ignition generator having pole piece projections; a stationary generating winding; a magnetic core for said winding; an insulated terminal connector for said winding comprising a conducting member having an electric connection with a terminal of said winding, a terminal post having fastening means for fastening an outside wire in electrical connection therewith, and a metal strip fastened at one end to said member and intermediate of its length to said post in electrical connection with both of them; and fastening means which mechanically fastens said strip near its other end to said core and electrically insulates them and which also fastens said core across said pole piece projections in magnetic contact therewith.

6. In an ignition generator having pole piece projections; a stationary generating winding; a magnetic core for said winding; an insulated terminal connector for said winding comprising a conducting member having an electric connection with a terminal of said winding, a terminal post having fastening means for fastening an outside wire in electrical connection therewith, and a metal strip mechanically fastened to said member and post in electrical connection with

both of them; and fastening means which mechanically fastens said strip to said core and electrically insulates them and which also fastens said core across said pole piece projections in magnetic contact therewith comprising a screw passing through said strip and said core into one of said pole piece projections, and insulating material insulating said screw and strip.

7. In a high tension ignition generator having two arms forming a portion of a stationary magnetic circuit thereof; a generating coil having primary and secondary windings; a magnetic core passing through said coil and seated on said arms; means for electrically connecting a grounded terminal of said primary winding to said core; an insulated terminal connector for said coil comprising a conducting member having an electric connection with terminals of said primary and secondary windings, a terminal post having fastening means for fastening an outside wire in electrical connection therewith, and a metal strip fastened to said member and terminal post in electrical connection with both of them; fastening means for mechanically and electrically connecting one end of said core to one of said arms; and other fastening means for mechanically fastening the other end of said core to the other of said arms and for mechanically fastening but electrically insulating said strip and core.

8. As a unitary element for a high tension ignition generator; a coil having primary and secondary windings; a magnetic core extending through said coil and being electrically connected to a grounded terminal of said primary winding; and an insulated terminal connector comprising a conducting member electrically connected to a live terminal of said primary winding and to a terminal of said secondary winding, a terminal post having fastening means for fastening an outside wire in electrical connection therewith, and a metal strip fastened to said member and post in electrical connection with both of them, said strip having a hole arranged for the passage of a screw and insulating member to mechanically fasten said strip to said core.

9. As a unitary element for a high tension ignition generator; a coil having impregnated primary and secondary windings; an insulating end disc having holes through which extend a live terminal of said primary winding and a terminal of said secondary winding; a magnetic core for said coil having a hole into which extends a grounded terminal of said primary winding; and an insulated terminal connector comprising a conducting member on the outside face of said disc and having holes which register with the holes in said disc and through which extend the terminals therein, a terminal post having fastening means for fastening an outside wire in electrical connection therewith, and a metal strip which is mechanically fastened to said member and post in electrical connection with both of them and which has a hole arranged for the passage of a screw and insulating member to mechanically fasten said strip to said core, said holes in said core and member being sealed in such manner as to prevent leakage of impregnating material from said core therethrough and to electrically connect the terminals therein.
